(57) **CLAIM**

The ornamental design for a freezer cabinet, as shown and described.

DESCRIPTION

FIG. 1 is a perspective view of my new design from above and the left;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof with the front and back reversed.

FIG. 8 is a perspective view from the front, left and above of an alternative view of my new design wherein the cover is open;

FIG. 9 an elevational view from the front of the design of FIG. 8 with the cover open to a perpendicular position;

FIG. 10 is an elevational view from the rear of the design of FIG. 8 with the cover open to a perpendicular position;

FIG. 11 is a left side elevation view of the design of FIG. 8;

FIG. 12 is a right side elevation view of the design of FIG. 8;

FIG. 13 is a top plan of the design of FIG. 8 taken from the front and above; and,

FIG. 14 is a bottom plan view of the design of FIG. 13 with the front and back reversed.

1 Claim, 12 Drawing Sheets
